No. 766,291.

PATENTED AUG. 2, 1904.

L. C. SMITH.

DRAWING MACHINE FOR TUBES, RODS, &c.

APPLICATION FILED JULY 17, 1903.

NO MODEL.

UNITED STATES PATENT OFFICE.

LESTER C. SMITH, OF ROME, NEW YORK.

DRAWING-MACHINE FOR TUBES, RODS, &c.

SPECIFICATION forming part of Letters Patent No. 766,291, dated August 2, 1902.

Application filed July 17, 1903. Serial No. 165,915. (No model.)

To all whom it may concern:

Be it known that I, LESTER C. SMITH, of Rome, in the county of Oneida and State of New York, have invented certain new and useful Improvements in Drawing-Machines for Tubes, Rods, &c.; and I do hereby declare that the following is a full, clear, and exact description of the invention which will enable others skilled in the art to which it appertains to make and use the same, reference being had to the accompanying drawings, and to the figures of reference marked thereon, which form part of this specification.

The object of my invention is to provide an improved drawing-machine for tubes, rods, &c., which is compact, effective in drawing and returning, and adapted to convenient and expeditious manipulation. With reference to the machine being compact it may be said that the ordinary drawing-machine of this class draws the material through the die as the piston or plunger moves away from the die, and taking into consideration the length of the cylinder, the necessary space between the die and cylinder, and the necessary space in front of the die to introduce the material the machines are very long and cumbersome and require a large amount of floor-space and a large amount of travel by the operators. As to being convenient and expeditious to manipulate, it may be said that ordinarily in machines of this class no provision is made for introducing the material with facility or removing it with facility, whereby the output of the machines is very much limited.

In the drawings, Figure 1 shows a plan view of a drawing-machine of my improved construction, parts being broken out to shorten the figure. Fig. 2 is a partial side elevation and a partial vertical section, the section being taken on line A B of Fig. 1. Fig. 3 is a cross-section taken on line C D of Fig. 1. Fig. 4 is an end view as seen from the left hand of Fig. 2. Figs. 5 and 6 shows attachments which may be provided for the machine.

Referring to the reference-figures in a more particular description, 1 indicates the frame, which is supported on pillars or stands 2, 3, and 4, rigidly secured thereto, and, in fact, constitute a portion of the frame.

Mounted on the frame and adapted to move from the middle portion toward one end thereof is the draw-head 5. This draw-head slides or runs on the table portion 6 of the frame, which constitutes a guide or way therefor. The table 6 is provided with a longitudinal slot 7, in which there runs a downwardly-projecting ear 8, attached to the draw-head 5. On the opposite end of the frame from the table part 6 there are provided the cylinders 10. The cylinders receive the plungers 11, which are substantially of the full diameter of the interior of the cylinder. The plungers 11 are connected directly to the drawing-head 5, preferably by the elongated bearing, which will obviate the tendency to skew. On the inner end the plungers 11 are provided with a roller 12, which runs on the inner surface of the cylinder and supports the weight of the plungers when they are drawn back into the cylinder. At the open end the cylinder is provided with a stuffed box 13. The cylinders are provided with a port 14, through which fluid (as water or oil) may be introduced into and removed from the cylinder. The ports 14 connect with the supply-pipe 15, which supply-pipe extends to a suitable pump or forcing apparatus and is provided with gate or valve for controlling the operation. Between the body portions of the cylinders 10 there is provided a dipping-tank 16, which may be formed as a portion of the frame. Between the end of the cylinders toward the draw-head there is provided a die-holder 17, adapted to hold the die 18, which is preferably removable and interchangeable.

The draw-head 5 is provided with a holding or gripping tongs consisting, as shown, of a pair of jaws 20 20. These jaws are supported in the draw-head by links 21 22, pivoted to the jaws and draw-head, respectively, and the jaws are connected, so as to move backward and forward together, by means of the cross-pin 23, secured to one and extending through an opening in the other, and rests on the table 6.

The length and arrangement of the jaws on the draw-head is such that the jaws will approach the drawing-die 18 very closely. At the rear end of the frame there is provided

an adjustable mandrel-holder consisting of the movable slide 30, having shoulders 31, adapted to engage the head or holding device on the shank of the mandrel 32. The slide 5 30 is movable longitudinal of the frame in the guides 33, and it is adjusted by means of a screw 34, extending through an ear in the slide 30 and engaging in a nut in the frame.

For returning the draw-head to starting position there is provided a block-and-tackle construction consisting of the large grooved wheel 40 and the smaller grooved wheel 41, mounted in fixed bearings on the frame, and the movable wheel or pulley 42, mounted on 15 a slide 43, attached to the piston-rod 44 of the cylinder 45. A chain 46 passes around these wheels, as shown, and is attached at one end to the lug or projection 8 on the draw-head and at the other to the slide 43 on the piston-rod 44. The cylinder 45 is provided with a supply-pipe 47, supplying fluid (as water or oil) to the end of the cylinder toward the slide 43. This pipe will be ordinarily open 20 at all times, supplying a constant pressure of fluid to the piston of the cylinder 45.

The operation of the device in Drawing 1, where the interior diameter, as well as the exterior, should be taken into account, is as follows: When the plungers are within the 25 cylinders, the gripping-jaw 20 stands close to the drawing-die 18. A section of tube to be drawn, which has previously been lubricated by dipping in oil or other lubricant in the tank 16, is inserted through the opening 30 in the die 18, the end having been previously reduced for that purpose, as is common in such practice. The mandrel 32 is then or has been previously inserted in the tube, and the shank thereof is engaged with the holding-shoulders 31, which are adjusted so that the 35 head of the mandrel will occupy a suitable position with reference to the die. The jaws 20 are closed onto the protruding end of the tube to be drawn, which is indicated by α , and the machine is started by opening the valve 40 which controls the supply of fluid through the pipe 15. By reason of the jaws resting on the table 6 and the arrangement of the links connecting the jaws or tongs to the draw-head the 45 tongs or jaws will automatically grip the material when the draw-head starts. This fluid, which is ordinarily oil or water, will be supplied, preferably, at a heavy pressure—that is to say, one thousand pounds to the square inch, 50 more or less. When the pressure is supplied, the plungers 11 are forced out of the cylinder, moving the draw-head 5 away from the die 18 and drawing the tube through the die, producing the desired reduction. The power of 55 the cylinder 10 is such that it will readily overcome the pressure of the fluid in the cylinder 45, which ordinarily will be supplied at a less pressure, as from a city water-main or other suitable source. As the tube is drawn

the plunger in the cylinder 45 is moved outwardly, forcing the contents of the cylinder out through the pipe 47. The sections of pipe drawn are regulated with reference to the length of the machine, so that at the time the draw-head has completed its travel, or previously, the section will be drawn entirely out of the die 18. As soon as the end passes out of the die the natural elasticity and springing parts will allow the jaws 20 to fly to open position and the tube is dropped on the table 6, from whence it is removed by the operator. After it is removed the pressure is cut off from the cylinders 10 10, and pipe 15, opened to the exhaust on the pressure on the cylinder 45 through the block-and-tackle 80 mechanism described, serves to immediately return the draw-head. The mandrel 32 being removed, a new section of tube to be drawn is provided and the operation repeated.

An automatic device for shutting off the supply of fluid to the cylinder 10 and opening the exhaust for the same may be provided, if desired. In case the machine is constructed for long draws it may be desirable to support the plungers 11 at intervals along the frame. For this purpose there may be provided arms 50, secured to the table or frame 90 6 at suitable intervals, which have an open-sided eye or loop 51 adapted to engage the plunger 11, put in the open side to allow the 95 passage of the draw-head 5.

In order to prevent the operators from coming in contact with the plunger 11, there may be provided a shield 55, supported by an arm 56 from the frame or table 6. The shield 55 100 may be provided at intervals where the operators will be employed or continuously along the side of the table, and the supports 51 and the shield 55 may be combined in a 105 continuous device, if desired.

When the machine is used for drawing rods, the mandrel 32 is of course dispensed with; but aside from this the operation of the machine is substantially the same.

What I claim as new, and desire to secure by Letters Patent, is—

1. In a drawing-machine of the character described, the combination of two cylinders spaced apart and closed at one end, plungers for the cylinders arranged to be projected out of the unclosed ends of the cylinders and coupled together by a draw-head, a die-holder between the cylinders at the end from which the plungers are projected, a die arranged to receive material at the side toward the closed ends of the cylinders, and deliver it at the other side, and tongs mounted on said draw-head facing the die and arranged to grasp and draw the material through the die on the thrust or projecting movement of the plungers, substantially as set forth.

2. In a drawing-machine of the character described, the combination of a cylinder closed

at one end, a plunger for the cylinder arranged to be projected from the unclosed end of the cylinder, a die supported adjacent to the unclosed end of the cylinder out of which 5 the plunger is projected, and arranged to receive material from the side toward the closed end of the cylinder, and deliver it from the other side, tongs secured to the projecting end of the plunger facing and adapted to be 10 brought into close proximity to the die, and arranged to grip the material automatically with the thrust or outward motion of the plunger, substantially as set forth.

3. In a drawing-machine of the character described, the combination of a pair of parallel cylinders spaced apart and closed at one end, and arranged in the same horizontal plane in a frame, plungers in the cylinders adapted to be projected from the unclosed end of the cylinders, a draw-head coupling together the 15 plungers, a delivery-table on the frame extending from the cylinders parallel with the line of movement of the plungers, and over which the draw-head operates, a die supported 20 between the cylinders and at the end of the table, and tongs mounted on the draw-head facing the die and arranged to be brought into close proximity to the die when the plungers are 25

withdrawn into the cylinders, substantially as set forth.

4. In a drawing-machine of the character described, the combination of a pair of parallel cylinders spaced apart and closed at one end, and arranged in the same horizontal plane in a frame, a receiving tank or table arranged 30 in the space between the cylinders, plungers in the cylinders respectively adapted to be projected from the unclosed ends, a draw-head coupling together the plungers, a die supported at the ends of the cylinders from which 35 the plungers are projected, and a tongs mounted on the draw-head facing the die and arranged to be brought into close proximity to the die when the plungers are withdrawn into the cylinders, and means for returning the 40 plungers into the cylinders and the tongs to their position adjacent to the die, substantially 45 as set forth.

In witness whereof I have affixed my signature, in presence of two witnesses, this 15th 50 day of July, 1903.

LESTER C. SMITH.
